CONTROL MECHANISM FOR THE DOORS OF MATERIAL DISTRIBUTING RECEPTACLES

George K. Viall, Milwaukee, Wis., assignor to
 Chain Belt Company, Milwaukee, Wis., a corporation of Wisconsin

Application April 2, 1947, Serial No. 738,998

6 Claims. (Cl. 214—59)

1

The invention relates to apparatus for distributing concrete or similar materials, of which the well known boom and bucket mechanism widely employed in conjunction with paving concrete mixers in the construction of roads, street pavements, etc. may be cited as a typical example. Such mechanism comprises a generally horizontal boom extending from the discharge end of the mixing machine and providing an elevated trackway upon which a receptacle or bucket is mounted for reciprocatory travel. The bucket, when moved to the inner end of the boom adjacent the mixer, receives the concrete as it is discharged from the mixer drum, subsequent to which the bucket is traversed along the boom to the point at which it is desired to deposit the mixture, whereupon a door or doors at the bottom of the bucket are opened to permit the contents to fall to the road bed by gravity action. Sometimes the complete batch is discharged at one location, while at other times it may be desirable to deposit only a part of a batch at one place and then move the bucket to another point for further discharge. In still other instances it may be wished to deposit the concrete as a ribbon, which is accomplished by maintaining the bucket doors partially or completely open during traverse of the bucket along the boom.

The bucket doors are controlled by the mixer operator from his usual station on the mixing machine, and in order that the concrete may be discharged from the bucket in any of the above described manners at will, it is essential that he have complete control over the bucket doors at all times, regardless of the position of the bucket on the boom, and of its rate and direction of travel thereon.

It is the principal object of the present invention to provide an improved remote control mechanism which gives the operator such complete control over the doors, to the end that he may at any time effect positive opening and closing movements of them to any desired extent within their limits of movement, and may maintain them in any position to which they are so moved for such times as may be necessary or desirable.

For purposes of disclosure the control mechanism constituting the invention has been illustrated in the accompanying drawings forming a part of this specification, as applied to such boom and bucket apparatus of a concrete mixer, although as will appear from the following description it may readily find other analogous applications.

In the said drawings, in which like reference

numbers designate like parts in all the views:

Fig. 1 is a side elevational view, partly broken away and in section, of a well known type of concrete mixer boom and bucket distributing apparatus equipped with one form of bucket door control mechanism constructed and arranged in accordance with the invention, the parts of such mechanism being shown in the positions they occupy when the bucket door is fully closed;

Fig. 2 is an enlarged longitudinal sectional-elevational view, on approximately the planes indicated by the line 2—2 of Fig. 3, showing the parts of the door control mechanism in the positions they assume when the door is in the fully open position indicated in broken lines in Fig. 1;

Fig. 3 is a plan view, partly broken away, of the essential parts of the apparatus shown in Fig. 2;

Fig. 4 is an end elevational view, as seen from the left of Fig. 2;

Fig. 5 is a diagrammatic perspective view illustrating the motions of the several gears of the control mechanism in the moving of the bucket door toward open position, the bucket being stationary on the boom;

Fig. 6 is a fragmentary plan view of a modified form of the invention, the parts being shown in the door-closed positions;

Figs. 7 and 8 are longitudinal sectional views, on approximately the respective planes indicated by the lines 7—7 and 8—8 of Fig. 6; the latter view showing the parts in an intermediate position; and

Fig. 9 is a cross sectional view on approximately the planes indicated by the line 9—9 of Fig. 7, looking in the direction of the arrows.

Referring first to Figs. 1—5 of the said drawings, the boom 11 comprises a pair of laterally spaced channel members 12 and 13, the inner ends of which are supported adjacent the discharge opening of the mixer drum (not shown) by a pin 14 which connects them to a boom swing pivot member 15 mounted by a portion 16 of the mixer frame. The lower flanges of the channels 12 and 13 constitute trackways for a bucket carriage 17 which is traversably mounted thereon by wheels or rollers 18. A bucket 19 is hung from said carriage by a mounting 20, and is provided with an oscillatory door 21 for controlling discharge of the bucket contents through the bottom discharge opening 22. From its closed position, shown in full lines in Fig. 1, this door may be swung in a clockwise direction

55 by linkage 23 to an open position, indicated in

broken lines, and back again, as is well known in the art. The bucket is traversed back and forth along the boom by an out-haul cable 24 and an in-haul cable 25, each fastened to the carriage 17 by a cable anchor 26 and passing around separate sheaves 27 journaled on pin 14 and thence upwardly through the eye of the boom pivot member 15 to a winding drum, not shown. The parts thus far described are conventional and well known in the art.

The mechanism of the present invention for actuating the linkage 23 whereby to move the bucket door 21 between its open and closed positions at will, comprises a differential gear unit mounted upon the carriage 17, and means whereby the functioning of such unit may be volitionally controlled by the operator from his station on the mixer to positively open and/or close the said door to any desired extent, and to hold it in any position to which it may be moved for such periods of time as may be necessary or desirable. The differential unit on the carriage may take various forms, that shown in Figs. 1-5 being of the planetary spur gear type, comprising a pair of spur gears 30 and 31 of equal diameters each rotatably mounted on an end portion of a shaft 32, the mid portion of which is journaled in a pedestal bearing 33 secured to the floor of the carriage 17 intermediate the boom channels 12 and 13. Intermediate the gear 30 and the bearing 33 the shaft 32 rigidly carries a pair of oppositely extending arms 34, the outer ends of which journal short shafts 36, each of which has a pair of spur pinions 37 and 38 rigidly secured thereto. These pinions are all of the same diameter, and the two pinions 37 are alined and mesh with the gear 30 at opposite sides thereof, while the two pinions 38 are disposed at substantially the longitudinal center line of the carriage 17. In like manner a second pair of oppositely extending arms 40 is secured to the shaft 32 intermediate the bearing 33 and the gear 31, these arms being somewhat circumferentially off-set with respect to the arms 34, as will be clear from Figs. 1 and 2. The outer ends of the arms 40 journal shafts 41, each of which rigidly carries a pair of spur pinions 42 and 43. These pinions are all of the same diameter as the pinions 37 and 38, and the pinions 42 are alined and mesh with the pinions 38, while the pinions 43 are alined and mesh with the gear 31. The left hand arm 40 is provided with an extension 44 which is pivotally connected at 45 to the upper end of the door-operating linkage 23.

The gear unit would be fully operative with but one set of pinions 37, 38, 42 and 43 and arms 34 and 40 carrying the same, and the right hand set of these elements is added merely to balance the device and distribute the load.

A rack 46 is fixedly secured to the upper portion of the boom channel 12 and extends substantially throughout the length of the latter in position for its teeth to engage with those at the top of the spur gear 30. A second rack 48 extends along the lower portion of the boom channel 13, being mounted for longitudinal reciprocation thereon by a dove-tail slide connection 47. The teeth of this rack 48 are engaged by those at the bottom of the spur gear 31, and the rear end of this rack is connected to the piston rod 49 of a double acting hydraulic ram or equivalent motor 50 carried by the rear end of the boom channel 13. Actuating fluid from any appropriate source of supply, not shown, may be supplied to and exhausted from the said motor at will

through conduits 51 extending to the operator's station on the mixer, where they are connected to any suitable control valve.

The bucket door 21 here shown is of a pendulous type which tends to maintain the closed position shown in full lines in Fig. 1, but the operation of the present control mechanism is in no wise dependent upon this characteristic, and it would function equally as well in connection with a self-opening type of door, such as that shown for example in the prior U. S. patent of Ball and Hilkemeier, No. 2,230,478 granted February 4, 1941.

In the apparatus here illustrated, the normal or door-closed position of the control mechanism is shown in Fig. 1, and so long as the slidably mounted rack 48 is maintained in the outward position there shown there will be no actuation of the door-operating linkage 23, whether the bucket be stationary on the boom or traversed in either direction thereon. If for example, the bucket be drawn inwardly along the boom (i. e. from left to right as viewed in Fig. 1) by the traverse cable 25, the gear 31 will roll upon its rack 48, rotating in a clockwise direction and driving its pinions 43 and 42 in a counterclockwise direction, while the gear 30 will be rotated by its rack 46 in a counterclockwise direction and will drive its pinions 37 and 38 in a clockwise direction. Since the ratios between the gears and their respective pinions are the same, the intermeshing pinions 37 and 42 will be driven in opposite directions at equal speeds and there will be no reaction tending to change the positions of the arms 34, 40 and 44 whereby to actuate the linkage 23. The same will be true during outward traverse of the bucket on the boom, except of course that the several gears and pinions will be rotated in directions opposite to those above described.

On the other hand, if while the bucket is either stationary on the boom or travelling in either direction thereon, the motor 50 be actuated to retract the slidable rack 48 from its Fig. 1 position toward or to the position shown in Fig. 2, the differential gear unit will function to actuate the linkage 23 and move the door 21 toward or to its broken line position in Fig. 1. Assuming for instance that the bucket is stationary on the boom, and referring to Fig. 5, the fixed rack 46 of course will hold the gear 30 against rotation while rightward movement of the rack 48 by the motor 50 will cause counterclockwise motion of the gear 31, which will drive pinion 43, shaft 41 and pinion 42 in a clockwise direction. The latter pinion in turn will drive pinion 38, shaft 36 and pinion 37 in a counterclockwise direction, and such movement of pinion 37 will cause it to react with the stationary gear 39 and revolve about it in a counterclockwise direction, thus depressing its carrying arm 34. The motion thus imparted to this arm is transmitted through the shaft 32 to the other pinion-carrying arm 40 and through its extension 44 to the door-operating linkage 23, thereby opening the door 21. The angular movement of the arms 34 and 40, and their pinions, is in the same direction as that in which the gear 31 is being rotated by the rack 48, but the rate of such arm and pinion motion is only one-half that of the gear movement.

The parts are so proportioned that a full stroke of the piston of the ram 50 will effect a complete movement of the door from one extreme position to the other, but since door movement occurs only as the rack 48 is moved relative to the rack 46, obviously if the ram piston be moved through only

a portion of its stroke the door will be opened or closed only to a corresponding extent.

As soon as motion of rack 48 ceases the gearing locks to prevent movement of the door in either direction and the door will thus be held in its new position until the rack 48 is again shifted. In the pendulous type of door here shown, the weight of the door tends to return it to its closed position, resulting in a constant upward push through linkage 23 to arm 44 tending to move such arm, together with the arms 40 and 34 and the pinions carried thereby, in a clockwise direction. Any such revolution of the pinions 43 and 31 about their now stationary gears 30 and 31 would require that each of such pinions rotate about its axis in a clockwise direction, which is impossible due to the fact that the intermeshing pinions 42 and 38 rigidly associated with said pinions 43 and 31 can rotate only in opposite directions. Thus, so long as the rack 48 remains stationary the gearing automatically prevents movement of the door; and the same would be true if the door were of the self-opening type shown in the above mentioned U. S. Patent No. 2,230,478, or if the door linkage were such as to exert a downward pull rather than an upward thrust on the arm 44.

Obviously, when the motor 50 is actuated to shift the rack 48 leftward from its Fig. 2 position the motions above described in connection with the opening of the door will occur in reverse, thus effecting closing movement of the door.

The mechanism will function in similar manners to either open or close the door while the bucket is being traversed in either direction along the boom. In these cases however, since as previously explained the gears 30 and 31 are rotating in opposite directions due to bucket traverse, the door operating movements are the result of increase or decrease in the rate of rotation of the gear 31 as compared to that of the gear 30, when the rack 48 is shifted. That is to say, if the bucket is traveling inwardly on the boom, the gear 30 will be rotating counterclockwise and the gear 31 clockwise, at equal speeds. If now the rack 48 be shifted toward the right the result is an acceleration of the gear 31 while the gear 30 maintains its same rate of rotation. Obviously, in effect this is the same as starting the gear 31 from a state of rest while holding the gear 30 stationary, and therefore the pinions 37 will react with the gear 31 to produce counterclockwise movement of the arms 34, 40 and 44 with consequent actuation of the linkage 23 to open the door. On the other hand, if with the bucket still traveling in the same direction, the rack 48 be shifted toward the left, the speed of the gear 31 relative to that of the gear 30 will be reduced, the arms 34, 40 and 44 raised, and the door closed. In this case however, the faster moving gear 30 acts as the driver, with the reaction which produces the movement of the arms taking place between the pinions 43 and the slower moving gear 31. It will nevertheless be in the proper direction to effect closing movement of the door.

With the bucket traveling outwardly on the boom the effect will be the same, except that here shifting of the rack toward the right will produce deceleration of the gear 31, while rack movement toward the left will accelerate such gear.

A second form of gearing suitable to ac-

complish the same general results is shown in Figs. 6-9, this unit being of the bevel differential type. This form of the invention is also illustrated as being provided with a reversing idler gear which permits both racks being disposed at either the bottom or the top of the boom channels, and which could be readily incorporated into the previously described form if desired.

Referring more specifically to these figures, 10 the unit comprises a bearing pedestal 60 secured to the floor of the carriage 17 and having a pair of alined bearings 61 and 62 journalling shafts 63 and 64 respectively. At one end the shaft 63 rigidly carries a spur gear 65 and at its other 15 end a bevel gear 66, while the shaft 64 rigidly carries a spur gear 67 and a bevel gear 68 in like positions, the two bevel gears facing one another, as will be readily understood from Figs. 6 and 9. A rectangular frame or pinion carrier 20 69 has its side members journaled on the shafts 63 and 64 between the respective bearings 61 and 62 and the associated bevel gears 66 and 68. The end members of the frame 69 have bevel pinions 70 and 71 rotatably mounted thereon, 25 which pinions are disposed between and in mesh with the bevel gears 66 and 68. An arm 72 is rigidly secured to one end of the frame 69 and has a pivotal connection 73 with the door-operating linkage 23.

30 A rack 74 is rigidly mounted on the lower portion of the boom channel 12, in position to engage the teeth of the spur gear 65 at the bottom thereof, while a rack 75 is longitudinally slidably mounted on the lower portion of the boom channel 13, below the spur gear 67. The rack 75 does not engage with the gear 67, motion being transmitted to the latter through the medium of an idler gear 76 carried by a shaft 77 journalled in a bearing 78 carried by an extension 40 of the pedestal 60. The spur gears 65, 67 and 76 are all of the same diameter and thus will rotate at equal speeds as the carriage 17 is traversed along the boom, although because of the interposition of the idler gear 76 between 45 the rack 75 and the gear 67, the latter gear together with its associated bevel gear 68 will rotate in a direction opposite to that of the gears 66 and 68.

The rack 75 of course is attached to a motor 50 similar to the motor 50 of the preceding form, whereby the rack may be reciprocated longitudinally to effect opening and closing movements of the door.

The operation of this form of the invention is 55 substantially the same as that of the spur gear type of unit described above. So long as the bevel gears 66 and 68 are rotated in opposite directions at equal speeds the pinions 70 and 71 merely idle and there is no reaction thereof 60 to produce actuation of the linkage 23. However, if the rack 75 be shifted in one direction or the other whereby to differentiate the speed of rotation of the gear 68 from that of the gear 66, the pinions 70 and 71 will be caused to revolve about the slower moving gear and through 65 their carrier 69 and arm 72 effect actuation of the linkage 23 in the proper direction to open or close the door as desired.

If the idler gear 76 were placed on the opposite 70 side of the unit, between the gear 65 and rack 74, the racks might be disposed along the tops of the boom channels instead of at the lower portions thereof, as here shown.

What is claimed is:

75 1. In apparatus for distributing concrete and

the like, the combination of a trackway; a material receptacle traversably mounted on said trackway and having a discharge controlling door; means for traversing the receptacle along the trackway in either direction at will; means connected to the receptacle door for actuating it between open and closed positions; a differential mechanism connected to said door actuating means for effecting movements thereof to open and close the door at will, regardless of the position or direction and rate of movement of the receptacle on the trackway, said mechanism comprising a pair of rack elements mounted upon and extending along the trackway, one of which elements is longitudinally movable relative to the other, and a planetary gear unit engaging said elements; and motive means connected to said mechanism for effecting differential operation thereof, said motive means being volitionally operable to varying extents to open and close the door to extents proportional to the movements of the motive means, the door remaining in any position it has attained when the motive means is at rest.

2. In apparatus for distributing concrete and the like, the combination of a trackway; material conveying means comprising a receptacle traversably mounted on said trackway, said receptacle having a door for controlling discharge of material therefrom; a differential gear mechanism mounted on said conveying means; connections between said differential mechanism and the receptacle door, whereby the latter may be moved by the former; means for traversing the conveying means and differential mechanism along the trackway; elements extending along the trackway for constant engagement with the differential mechanism throughout said traverse and normally preventing differential action of said mechanism whereby to maintain the receptacle door in any given position; and volitionally operable means for controlling one of said elements whereby to cause differential action of said mechanism with consequent movement of the door to a new position.

3. In apparatus for distributing concrete and the like, the combination of a trackway; material conveying means comprising a receptacle traversably mounted on said trackway, said receptacle having a door for controlling discharge of material therefrom; a differential gear mechanism mounted on said conveying means; connections between said differential mechanism and the receptacle door, whereby the latter may be moved by the former; means for traversing the conveying means and differential mechanism along the trackway; a pair of elements extending along said trackway for constant engagement with the differential mechanism, said elements being mounted for relative movement between them and in the absence of such movement functioning to prevent differential action of said mechanism whereby to maintain the receptacle door in any given position; and means operable at will to vary the positions of said elements relative to one another, whereby to produce differential action of said mechanism with consequent movement of the door from its said position.

4. In apparatus for distributing concrete and the like, the combination of a trackway; material conveying means comprising a receptacle traversably mounted on said trackway, said receptacle having a door for controlling discharge of material therefrom; a differential unit mounted on

said conveying means, comprising a pair of gears, pinions driven by said gears, and means mounting said pinions for revolution about the gears; connections between said pinion mounting means and the receptacle door, whereby the latter may be moved by the former; means for traversing said conveying means and differential unit along the trackway; a rack for each of said gears, mounted upon and extending along the trackway, for imparting equal and opposite rotation to the gears during said traverse whereby to prevent revolution of the pinions about the gears and thus maintain the receptacle door in any given position, one of said racks being mounted for longitudinal movement relative to the other; and means operable at will to shift said movable rack whereby to accelerate or decelerate one of the gears relative to the other and thus produce revolution of the pinions about the gears with consequent movement of the door to a new position.

5. In apparatus for distributing concrete and the like, the combination of a trackway; material conveying means comprising a receptacle traversably mounted on said trackway, said receptacle having a door for controlling discharge of material therefrom; a differential unit mounted on said conveying means, comprising a pair of axially aligned gears, a set of pinions associated with each gear, each such set comprising a pinion meshing with one of the gears and a pinion meshing with the like pinion of the other set, and carrier means for the pinion sets mounting them for revolution about the gears; connections between said carrier means and the receptacle door, whereby the latter may be shifted by movement of the former; means for traversing said conveying means and differential unit along the trackway; a rack for each of said gears, disposed along the trackway, said racks being arranged to impart equal and opposite rotation to the gears during said traverse whereby to prevent revolution of the pinions about the gears and thus maintain the receptacle door in any given position, one of said racks being mounted for longitudinal reciprocation relative to the other; and power means connected to said movable rack and operable at will to shift the same, whereby to increase or decrease the speed of its gear relative to that of the other gear and thus produce revolution of the pinion sets with consequent movement of the door to a new position.

6. In apparatus for distributing concrete and the like, the combination of a trackway; material conveying means traversably mounted on said trackway, comprising a receptacle having a door for controlling discharge of material therefrom; a differential unit mounted on said conveying means, comprising a pair of aligned driving gears and a differential gear device between them having a pinion carrier movable through differential motion of said driving gears; connections between said pinion carrier and the receptacle door, whereby the latter may be shifted through movement of the former; means for traversing said conveying means and differential unit along the trackway; a pair of racks extending along the trackway in position to impart equal and opposite rotation to said driving gears during such traverse, whereby to prevent movement of said pinion carrier and thus maintain the receptacle door in any given position, one of said racks being mounted for longitudinal reciprocation relative to the other; and a motor mounted on the trackway and connected to said

movable rack, said motor being operable at will to shift such rack whereby to produce the differential movement of the driving gears necessary to effect movement of the pinion carrier and shifting of the door.
